US00D965409S

(12) **United States Design Patent** (10) **Patent No.:** **US D965,409 S**
Bullock et al. (45) **Date of Patent:** **** Oct. 4, 2022**

(54) **LATCH PORTION**(71) Applicant: **YETI Coolers, LLC**, Austin, TX (US)(72) Inventors: **Dustin Bullock**, Austin, TX (US); **John Loudenslager**, Austin, TX (US); **John Fritz**, Austin, TX (US); **Michael Christopher Cieszko**, Austin, TX (US); **Andrew J. Winterhalter**, Austin, TX (US)(73) Assignee: **YETI Coolers, LLC**, Austin, TX (US)(***) Term: **15 Years**(21) Appl. No.: **29/794,646**(22) Filed: **Jun. 14, 2021****Related U.S. Application Data**

(63) Continuation of application No. 29/711,745, filed on Nov. 1, 2019, now Pat. No. Des. 922,176, which is a continuation of application No. 16/218,089, filed on Dec. 12, 2018, now Pat. No. 10,766,672.

Primary Examiner — Doris Clark(74) *Attorney, Agent, or Firm* — Banner & Witcoff, Ltd.(57) **CLAIM**

The ornamental design for a latch portion, as shown and described.

DESCRIPTION

FIG. 1 is a front, right, perspective view of a latch portion showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines form no part of the claimed design.
